UNITED STATES PATENT OFFICE.

WILLIAM HENRY BAKER, OF NEW YORK, N. Y.

DOUBLE-ACTING COMBINATION-LOCK VALVE FOR BARRELS, &c.

SPECIFICATION forming part of Letters Patent No. 743,134, dated November 3, 1903.

Application filed November 21, 1902. Serial No. 132,294. (No model.)

To all whom it may concern:

Be it known that I, WILLIAM HENRY BAKER, a citizen of the United States, and a resident of the city of New York, borough of Manhattan, in the county and State of New York, have invented a new and Improved Double-Acting Combination-Lock Valve for Barrels, &c., of which the following is a full, clear, and exact description.

10 My invention relates to double-acting combination-lock valves for use more particularly upon receptacles, such as barrels, &c., the idea being not only to prevent the contents of the receptacle from being removed by unauthorized persons, but also to prevent the removal of the valve itself from the receptacle.

Reference is to be had to the accompanying drawings, forming a part of this specification, in which similar characters of reference indicate corresponding parts in all the figures.

Figure 1 is a perspective view showing the invention ready to be applied to a barrel or similar receptacle. Fig. 2 is a central section of the same, slightly enlarged, and showing it as applied to a barrel; and Fig. 3 is a plan view of the plug, showing the keyhole.

This invention may, if desired, be used in connection with the lock-valve covered by my United States Patent No. 717,237, dated

30 October 28, 1902.

A stave 1 of the barrel is provided with bolt-holes 2 3 and with a threaded bung-hole 5, which is normally engaged by a threaded pipe 4. A casing 6 is provided with a spout 7, preferably secured thereto by screw-threads 8, as indicated in Fig. 2. The threaded pipe 4 is screwed by means of threads 5^a into the casing 6.

A revoluble plug 9 is provided with an aperture 10, through which the fluid normally passes. This plug 9 is hollow and contains a locking mechanism, which is preferably the same as that shown and described in my above-mentioned patent. I do not limit myself, however, to the particular mechanism shown and described in said patent, as any other suitable locking mechanism may be used. The plug is provided with an angular head 12 for the purpose of rotating the plug 9 by means of a wrench or by means of the fingers. A closure-lid 13 is hinged upon the

angular head 12, which is integral with the cap 11, and which may be removed for the purpose of gaining access to the interior portions of the plug.

55 Lugs 14 15 serve as limiting-stops for preventing excessive rotary movements of the plug 9. A revoluble key-post 16 is provided with a keyhole or slot 17 for the purpose of operating the locking mechanism. The casing 6 is provided with holes 18 19, into which the bolts 20 21 may enter. A large bolt 22 is provided with a tongue 23 and a bead 24, disposed within the bolt-hole 18, and normally occupies the position indicated in the upper 60 portion of Fig. 2. In the lower portion of the casing 6 is a somewhat smaller bolt-hole 25, in which is a bolt 26, provided with a tongue 27 and with a bead 28. The beads 24 28 are normally engaged by the revoluble 70 plug 9.

A washer 30 is provided at the lower end of the plug 9 and is secured in place by a nut 31, mounted upon a stem 32.

The operation of my device is as follows: 75 One end of the threaded pipe 4 is screwed tightly into the casing 6, as indicated in Fig. 2. The other end of the threaded pipe is thereupon screwed into the bung of the barrel. The bolt-holes 2 3 are disposed adjacent 80 to the bung-hole, so as to register with the bolt-holes 25 and 18, as indicated in Fig. 2. The bolts 22 and 26 are next slipped outwardly or in the general direction of the barrel, being thus caused to engage the bolt-holes 2 and 3. The revoluble plug 9 is next placed in the position indicated in Fig. 2. By means of a key the revoluble post 16 may be turned and the lock operated in the usual manner, so as to throw the bolts 20 and 21 90 into the position indicated in Fig. 2 and to withdraw the same into the plug. When the bolts are withdrawn from the apertures 18 19, the plug may be rotated by means of the angular head 12; but the beads 24 and 28 95 still remain in contact with the revoluble surface of the plug. This fact prevents the withdrawal of the larger bolts 22 26, and thereby prevents the casing 6 from being unscrewed from the barrel. It matters not 100 whether the valve proper be locked or unlocked; it is equally impractical for unau-

thorized persons to remove the casing 6 for the reason that the same cannot be turned upon the threaded pipe 4, because of the presence of the bolts 22 26 in the bolt-holes 5 23 of the barrel proper. It is only by removing the revoluble plug 9 from the casing that the bolts 22 26 can be withdrawn, and, as will be seen from Fig. 2, it is impossible to remove the revoluble plug 9 so long as the bolts 20 21 engage the apertures 18 19. The lock of the valve therefore serves not only to prevent the surreptitious removal of the contents of the barrel, but also serves to prevent the withdrawal of the bolts 22 26.

15 The purpose of the beads 24 and 28 is to facilitate the removal of the large bolts 22 and 26. This is accomplished by first removing the plug 9 and then by means of the finger-nail engaging the beads 24 28 and drawing 20 the bolts 22 26 through the bolt-holes 18 25.

25 My invention permits of an endless variety of uses, such as will readily suggest themselves to persons in the various arts to which it relates.

Having thus described my invention, I claim as new and desire to secure by Letters Patent—

30 1. A double-acting combination-lock valve for barrels, &c., comprising a casing, a threaded member connected therewith and adapted to be screwed into the bung of a barrel, bolts for normally preventing relative movements between said casing and said barrel, and means, controllable at will, for preventing the removal of said bolts.

35 2. A double-acting combination-lock valve for barrels, &c., comprising a casing, a threaded member connected therewith and adapted to be screwed into the bung of a barrel, bolts for normally preventing relative movements 40 between said casing and said barrel, and locking mechanism, controllable at will, for normally preventing the withdrawal of said bolts.

45 3. A double-acting combination-lock valve for barrels, comprising a casing, a threaded member connected therewith and adapted to be screwed into the bung of a barrel, bolts for normally preventing relative movements 50 between said casing and said barrel, and means for normally preventing the removal of said bolts.

55 4. A double-acting combination-lock valve for barrels, comprising a casing, a threaded member connected therewith and adapted to be screwed into the bung of a barrel, bolts for normally preventing relative movements 60 between said casing and said barrel, and a removable valve-plug mounted within said casing and normally engaging said bolts.

65 5. A double-acting combination-lock valve for barrels, &c., comprising a casing, a threaded member connected therewith and adapted to be screwed into the bung of a barrel, bolts for normally preventing relative movements 70 between said casing and said barrel, a remov-

able valve-plug mounted within said casing and normally engaging said bolts, and locking mechanism mounted within said valve-plug for normally preventing the removal of said bolts.

75 6. In a double-acting combination-lock valve for barrels, &c., the combination of a receptacle provided with bolt-holes, a casing mounted upon said receptacle and free to revolve relatively thereto, said casing being provided with bolt-holes free to mate said bolt-holes of said receptacle, bolts mounted within said bolt-holes in said casing and free to engage said bolt-holes in said receptacle, and means for normally preventing the withdrawal of said bolts from said bolt-holes of said receptacle.

80 7. In a double-acting combination-lock valve for barrels, &c., the combination of a receptacle provided with bolt-holes, a casing 85 mounted upon said receptacle and free to revolve relatively thereto, said casing being provided with bolt-holes free to mate said bolt-holes of said receptacle, bolts mounted within said bolt-holes in said casing and free to engage said bolt-holes of said receptacle, and a valve-plug removably mounted within said casing and normally engaging said bolts, thereby preventing the withdrawal of the same from said bolt-holes of said receptacle.

90 8. In a double-acting combination-lock valve for barrels, &c., the combination of a receptacle provided with bolt-holes, a casing mounted upon said receptacle and free to revolve relatively thereto, bolts slidably mounted within said casing and free to engage said bolt-holes, a valve-plug removably mounted within said casing and normally engaging said bolts, thereby preventing the withdrawal thereof from said bolt-holes of said receptacle, and locking mechanism for normally preventing the removal of said plug from said casing.

95 9. In a double-acting combination-lock valve for barrels, &c., the combination of a receptacle provided with bolt-holes, a casing mounted upon said receptacle and free to revolve relatively thereto, bolts slidably mounted within said casing and free to engage said bolt-holes, a valve-plug removably mounted 100 within said casing and normally engaging said bolts, thereby preventing the withdrawal thereof from said bolt-holes of said receptacle, and locking mechanism for normally preventing the removal of said plug from said casing.

105 10. In a double-acting combination-lock valve for barrels, &c., the combination of a receptacle provided with bolt-holes and with a bung-hole disposed adjacent to the same, a 110 casing provided with a threaded member to be screwed into said bung-hole, and also provided with apertures, bolts slidably mounted within said casing and free to engage said bolt-holes of said receptacle, said bolts being 115

120 125 130

provided with apertures and with tongues disposed adjacent to said apertures, a revoluble plug mounted within said casing and normally engaging said tongues, a plurality of 5 bolts slidably mounted within said plug and free to engage said apertures of said casing.

In testimony whereof I have signed my

name to this specification in the presence of two subscribing witnesses.

WILLIAM HENRY BAKER.
